UMBRELLA, PARASOL, OR THE LIKE

Sydney Murdoch Frost, Leicester, England, assignor to Kendall & Sons Limited, Leicester, England

Application March 16, 1949, Serial No. 81,689
In Great Britain November 22, 1947

4 Claims. (Cl. 135—36)

1

The present invention relates to means for securing the covers of umbrellas, parasols and sunshades (hereinafter termed umbrellas) to the ribs of the umbrella-frame or to members constituting extensions thereof.

In the specification of co-pending application Serial No. 701,593 by Samuel Duncan Cathcart, filed October 5, 1946 there are described and claimed umbrellas wherein the cover is secured to the outer ends of the ribs of the frame or to members constituting extensions thereof by rivets, which are not formed integrally with the ribs and which pass through separate bushed eyelets of the said cover at or adjacent to its periphery.

By the term "bushed eyelet," is meant a light tube which has outwardly deformed ends which grip the fabric of the cover, with or without the aid of interposed washers, one at least of the outwardly deformed ends being formed by deforming an end of the tube after passing through the fabric. Bushed eyelets of aluminium or aluminium alloy have the desired ductility and also may be anodised to wide variations of colours and they also tend to avoid damage to plastic rib extension members when these are used. The bushed eyelets may be made of or covered or coated with plastic material, which may be suitably coloured or they may be sprayed or otherwise coated with colour. The whole or part or at least the heads of the rivets may also be treated as aforesaid or in the case of aluminium rivets they may be anodised as aforesaid. The bushed eyelets keep the stem of the rivet or stud out of contact with the material of the cover which is securely held between the radially extending portions of the eyelets.

I have found that there is a risk that the riveting pressures necessary to swage the headless end of a solid rivet may damage the anodised or coated surface of the rivet and the anodised or coated or other surface of the bushed eyelet and the appearance of the umbrella is marred.

The object of the present invention is to reduce the riveting pressure, thereby lessening the tendency to damage the said anodised or coated surface.

In order that the present invention may be the more clearly understood, reference is herein-after made to the accompanying drawings which illustrate by way of example one form of the invention and in which:

Fig. 1 is a half view partly in section of an umbrella according to the present invention.

Fig. 2 is an enlarged sectional view of one of the eyelets before application to the cover; Fig. 3

2

is an enlarged sectional view of one of the rivets; Fig. 4 is a perspective view of one of the extension members and Fig. 5 is a section of the extension member fitted on the end of a rib of the umbrella frame and showing the eyeleted cover secured thereto by means of the swaged rivet and Fig. 6 is an enlarged view of part of Fig. 5.

Referring to the drawings, the cover 1 is provided around its periphery with a series of bushed eyelets 2 which may be secured through the cover at the outer end of each radial seam thereof for example in any of the ways described and illustrated in the aforesaid specification. The unflanged end of each eyelet tube (Fig. 2) is deformed so that the eyelet grips the cover as shown in Fig. 5.

The outer end of each rib 3 of the umbrella frame is fitted with an extension member 4 provided with a socket portion 5 to fit over the end 10 of the rib. The extension member is provided with a cross passage 6, which opens at one end into a groove or recess 7 in which the eyelet seats and the other end of the passage is countersunk at 8.

25 The rivets 9 are of hollow tubular form with a radially projecting flange 10 at one end (see Figs. 3 and 5) which is annularly dished at 11 to receive a flange of the eyelet and substantially to conform to the configuration thereof. The end 30 of the rivet is closed by an end wall 12 which is shown (Fig. 3) at right angles to the axis of the rivet and rounded at its margin.

With the eyelet seated in the groove or recess 7 of the extension member, the rivet is passed through the eyelet and the cross passage 6 and the centre of the closed end of the rivet is forced in to form a closing or locking swage which secures the bushed eyelet to the extension member. The several eyelets round the cover may be each 40 riveted to an extension member before the cover and attached extension members are applied to the ribs.

The bushed eyelets are preferably made of a ductile material such as aluminium for the purpose previously described.

45 The hollow rivets may be colour sprayed or dipped and the reduction of the swaging pressures permitted by the invention lessens the risk of such finish or surface being detrimentally affected by the swaging operation.

The requisite thickness of the wall of the hollow rivet may be ascertained by test, a thickness of 0.010 inches serving well, and much less pressure is required to set a hollow-rivet having its thickness than is needed to set a solid rivet.

For setting the rivet, a setting hammer with

a conical working end having an apex angle of 120° serves well.

For colour finishing the hollow rivets, a number of these may be inserted flanged end uppermost in holes in a block or plate and the whole immersed in a colour bath.

The hollow rivets may be filled with colour or other deformable substance.

Coating by spraying may be practised with both the eyelets and the rivets, and in the case of the hollow rivets spraying may be prolonged sufficiently to fill the same.

The hollow rivets may advantageously be made of chromium plated brass or of aluminium and may in the latter case be anodised to wide variations in colour, the low swaging pressures permitted by the present invention lessening the risk of the plating or anodised surface being detrimentally effected by the swaging operation.

The eyelets may be riveted directly to the ribs, for example, by shaping the rib ends as shown in Fig. 10 of the specification of application Serial No. 701,593 and passing the rivets through such shaped ends.

What I claim is:

1. An umbrella comprising a cover and a frame having cover-supporting ribs, members constituting extensions of the outer ends of said ribs, tubular eyelet members inserted through and clamped to the perimeter of the cover, and hollow tubular rivet members separate from said ribs and extension members and passing through said eyelet members, one end of each said hollow rivet member having a radially projecting flange and the other end being closed but readily deformable and being deformed to secure the eyelet to the said extension member.

2. An umbrella according to claim 1, in which said flange of the rivet member is annularly dished and the cloth is clamped between flanges of the eyelet, that flange of the eyelet member adjacent the flange of the rivet member being

dished and the flange of the rivet member substantially following the contour of the said flange of the eyelet and not extending substantially beyond the perimeter of said eyelet flange.

3. An umbrella according to claim 1, in which said extension members and said outer ends of the ribs engage plug and socket fashion, each said extension member having a cross passage, the stem of the hollow tubular rivet member passing through the eyelet and then through the said passage, the inner end of said passage being countersunk and the closed end of said rivet member being swaged into said countersink by forcing the centre of the closed end axially inwards so that the rivet expands radially at that end to form a locking swage which effectively secures the eyelet to the extension member.

4. An umbrella comprising a cover and a frame having cover-supporting ribs, tubular eyelet members inserted through and clamped to the perimeter of the cover, and hollow tubular rivet members separate from said ribs and extending through said eyelet members, one end of each said rivet member having a radially projecting flange and the other end being closed but readily deformable and being deformed to secure the eyelet to the rib.

SYDNEY MURDOCH FROST.
